HAT BRIM CURLING MACHINE

Marcel Cassé, Essonnes, France

Application January 3, 1938, Serial No. 183,192
In France February 17, 1937

4 Claims. (Cl. 223—14)

The automatic machines for curling hat brims, i. e. for shaping the edge of said brims, comprise two principal mechanisms: an oval turning mechanism or oval lathe, upon the plate of which 5 is secured the hat, and a curling tool consisting essentially of a rotary wheel which presses upon the upper face of the hat brim and obliges it to assume the shape of a groove which is formed in a hot iron. The edge of the hat brim is previous- 10 ly moistened by a workman by means of a wet sponge. Owing to said moistening operation, and also to the fact that the known machines, when at work, require the interference of the workman for the reasons which will be herein- 15 after set forth, the workman can only work a single machine.

The known machines have a common general arrangement. The hat is mounted in the upright position, i. e. with the crown above the brim, on the plate of the machine. In these 20 conditions, the curling wheel and its driving mechanism are situated above the hat brim, and this latter may become stained by the oil or grease used with such mechanisms. More- 25 over, the devices which transmit the movement to said oval lathe, on the one hand, and to said wheel on the other hand, while permitting said wheel of being moved back for the insertion of the hat and of being displaced in order to provide 30 for curls of different sizes, are of course of a rather complicated construction, as said devices must so to speak surround the hat since the drive of said oval lathe is located below and the wheel above the hat rim.

Finally, it is difficult to utilize an automatic 35 device for moistening the edge of the hat brim, for instance by a supply of steam, as any excess of water will wet the plate and will flow upon the hat brim.

On the other hand, the oval lathe in general 40 use in brim curling machines is an elliptical lathe provided with two guides, or is a modification of the elliptical lathe by the deformation of the two guides of said lathe. It is a known fact that 45 such a mechanism is defective from the fact that it does not bring each point of the oval defining the hat brim against the wheel in a fixed direction tangent to the said wheel. For this reason, the curling will be unequal on the "temples" of 50 the hat brim.

The present invention has for its object to provide 55 an improved hat brim curling machine, which obviates the drawbacks of the known machines, which is simple, economical and effective and in which, according to a first feature

of the invention, the hat is disposed with the crown downwards and the brim upwards.

This disposition permits of placing all the mechanical devices below the plane of the hat brim, thus obviating all dropping of grease or 5 oil upon the hat. On the other hand, it provides for the ready mounting of a device for moistening the edge of the hat brim, so that on the one hand the water or steam, or a mixture of the same, may be brought direct upon the 10 normally lower face of the hat brim, which is positioned upwardly and will engage the hot iron, and on the other hand, all excess of water will flow away naturally and will not soil the hat.

According to a further feature, the oval lathe 15 by which the hat is rotated is constituted, as known per se, in such a manner that each point of the oval defining the edge of the hat brim is brought in contact with the curling tool in such a way that the tangent to this oval at said point 20 will coincide with a fixed direction, which is tangent to the curling tool.

Preferably, the driving shaft of the oval lathe has a variable eccentricity, thus providing for 25 variations of the oval trajectory of the hat and hence for unequal curls at the sides, at the front and/or at the back of the hat brim, if the oval described by the lathe does not coincide with the oval defining the hat brim.

According to a further feature, the axis of the 30 hat may be made eccentric with reference to the axis of the driven member of the oval lathe, and this will permit of obtaining an unequal curling at the front and back of the hat brim.

According to further features: 35
The vertical driving shaft of the oval lathe and the vertical shaft of the rotary wheel, are actuated by means of two pairs of worm gearing pertaining to a single horizontal shaft which receives itself the movement for driving the machine; 40

The iron which is heated electrically or by gas is mounted on the end of a pivoted arm, which provides for its ready moving away from the hat brim when the operation is finished. 45

In the accompanying drawings which are given solely by way of example:

Fig. 1 is a vertical longitudinal section on the line 1—1 of Fig. 3, of a machine in conformity with the invention. 50

Fig. 2 is a horizontal section on the line 2—2 of Fig. 1.

Fig. 3 is a side view.

In the embodiment herein represented, the hat 55 is placed in the inverted position within a sort

of oval pot 2, and the band 3 of the hat is maintained by a slightly tapered form piece 4 placed in the interior of the crown of the hat. The base 5 of the pot 2 rests upon an oval plate 6, and is set in motion by means of two studs 7 carried by said plate.

The oval plate 6 rests upon a cylindrical member 8 having a vertical axis AA, which causes said plate to rotate by means of a key 9 for example. The plate 6 is slidable on the member 8 in the direction of the large axis of its oval, i. e., parallel with the plane of Fig. 1. A nut 10, screwed on a screw 11 is adapted to hold the plate 6 stationary with reference to member 8. Member 15 8 forms the actuated part of an oval lathe of a well known type, by which the hat 1 can be rotated in such a manner that the tangent to the hat brim at a point fixed in space, through which the various points of the hat brim pass in succession, will have a fixed direction.

Said lathe will be hereinafter described.

Member 8 comprises an internal tooth ring 12 and a cylindrical bore 13.

By means of this bore, member 8 is rotatable 25 on a member 14. This latter is pivotally mounted, on a spindle 15 the axis CC of which is parallel with the axis AA, upon a plate 16 which is slidable, in a direction parallel with the plane of Fig. 1, upon the upper face, provided with guides, 30 of a casing 18. Said casing is slidably mounted, by means of guides 19 (Fig. 3), parallel with the plane MM (Fig. 2), upon a second casing 20 which is mounted in a fixed position on the main frame 21. A hand wheel 122 (Fig. 3) permits, by 35 a suitable screw and nut device, of displacing the casing 18 upon the casing 20, in a direction parallel with the plane MM.

The internal toothring 12 of member 8 meshes with a pinion 21 the diameter of which is equal 40 to the radius of the ring 12. Said pinion is keyed to a spindle 22 the axis BB of which is parallel with the axes AA and CC and is equidistant from these axes. Spindle 22 is rotatable in a bore 23 in the oscillating member 14, and is terminated 45 at its lower part by a slide 24 which is slidable in horizontal guides 25 formed in a member 26 secured to a shaft 27 having a vertical axis DD and which is rotatable in the base of the casing 18. The movements of the slide 24 upon the 50 member 26, which serve to vary the eccentricity of the axis BB with reference to the axis DD, from a zero value upwards, are effected for instance by means of a screw 28 journaled in the member 26 and screwed into a movable nut 29 which is secured by a screw 30 to the slide 24 and to the spindle 22.

The shaft 27 the axis of which is DD, has keyed to it a worm-wheel 128. Said wheel is in mesh with a worm 129 formed upon a shaft 130 which 60 is rotatable in the fixed casing 20. To shaft 130 is keyed the driven part 31 of a clutch device the driving part of which consists of a pulley 32. The hub 132 of said pulley is rotatably and slidably mounted on a sleeve 33 which is concentric 65 with the shaft 130 and is secured at 34 to the casing 20. The movements of the hub 132 upon the said sleeve, for the coupling or uncoupling, at 35, of the members 31 and 32, are effected for instance by means of claws 36 secured to a ring 70 37 mounted on the fixed sleeve 33. Ring 37 carries a stud 38 (Figs. 2, 3) engaging a helical groove 39 in the sleeve 33, so that it is simply necessary to turn sleeve 33 in the direction of the arrow f¹ (Fig. 3) in order to displace longitudinally said sleeve in the direction of the arrow

f² (Fig. 2), thus uncoupling the device at 35. The rotation of the sleeve 37 in the direction of the arrow f¹ is effected, against the action of a clutch spring 39 (Fig. 3), by a lever 40 acting upon a finger 41 pertaining to the sleeve 37. The lever 40 is keyed to a shaft 42 which is journaled in bosses 43 of the casing 20. To the other end of the shaft 43 is keyed a lever 44 the forked end of which is situated below a stop 45 carried by a rod 46 leading to a pedal, not shown, which is located at the bottom of the machine, so that it is simply necessary to press down this pedal in order to uncouple shaft 130.

To said shaft 130 is keyed a worm-wheel 47 (Figs. 1 and 2) which is in mesh with a worm 15 48 keyed to a vertical shaft 49 the vertical axis of which is situated in the plane MM. Shaft 49 is journaled in bearings 50 and 51 carried by a support 52 secured to the fixed casing 20. Shaft 49 extends upwardly beyond the said support, 20 and its end forms a spindle 53 to which is secured a rod 54 carrying the curling wheel 55 which is thus removable and can hence be selected, as regards its outline, so as to suit the type of curled rim which is desired for the hat 1.

Said wheel 55 may engage a groove 56 of a heating iron 57, the heating of which may be effected by any suitable means, such as steam, hot air, or electricity. The iron 57 is mounted on a cylinder 58 which fits upon a supporting arm 59 30 and the height of which is adjustable by a screw 60 which is rotatable in the cylinder 58 and is screwed into the arm 59.

Said arm 59 is pivotally connected, through pivot 61, to the support 52. A spring 62 tends to 35 pivot the arm 59 in the direction of the arrow f³ (Fig. 1), that is, in the direction in which it is applied against the wheel 55. A screw 63, forming an adjustable stop, serves to limit the pivoting movement of the arm 59 in the direction 40 of the arrow f³. Said arm can be reected from the wheel 55 against the action of the spring 62, by a rod 46 which is pivoted at 64 to the said arm 59. This arm can be held in the separated position by a stop 65 which is pivoted at 66 to the 45 support 52.

The machine is completed by a nozzle 166 which serves to supply water and/or steam for moistening purposes, upon the normally lower face (now turned upwardly) of the hat rim 1, 50 adjacent the member 57 and back of this member with reference to the direction of rotation of the hat.

The operation is as follows: In the idle position, the arm 59 is held away from the wheel 55 by the stop 65, the rod 46 is lowered, and the shaft 130 is thus uncoupled. The pot 2 is stopped, as well as the wheel 55.

The hat 1 to be curled is placed in the pot 2 and is fitted with the form piece 4. The arm 59 is released from the stop 65, and the workman allows the clutch pedal, and hence the rod 46, to slowly rise. The arm 59 pivots, in the direction of the arrow f³, and the member 57 now presses the rim of the hat 1 between the wheel 55 and the wall of groove 56, the hat rim having been engaged between these parts. At the same time, the lever 40 presses against the arm 41 (Fig. 3) of the clutch ring 31, thus coupling the pulley 32 to the wheel 31. The shaft 130 is thus set in 70 rotation, and—through the worm 129 and the wheel 47—it rotates the journal 27 and the shaft 49.

The shaft 27 drives the entire oval lathe. The axis AA, while rotating about itself, also describes 75

an oval, in the known manner, in such a manner that the pot 2 will bring all points of the hat brim in succession between the wheel 55 and the heating iron 57. The oval described by each point of the shaft AA will depend, as known, upon the eccentricity between the axes BB and DD, and this eccentricity is adjustable by means of the screw 28 which permits of displacing the slide 24 relatively to the member 26 carrying the journal 27.

The curling operation is completed when the entire hat brim has passed between the members 55 and 57.

It is simply necessary to press down the pedal 15 in order to uncouple the device, so moving back at the same time the hot iron 57, due to the pivoting of the arm 59 in the contrary direction to the arrow f³.

It should be observed that owing to the use of 20 said oval lathe of a known type, the hat brim is always brought with the same orientation between the members 55 and 57, i. e., the tangent to the edge of the hat, adjacent the said members, will always coincide with the common tangent of these members. This will provide for an 25 equal curling on both "temples" of the hat brim.

Owing to the possible displacement of the pot 2 and the plate 6 upon the member 8, it is feasible 30 to make the axis of the pot 2 and hence the axis of the hat 1 eccentric with reference to the axis AA of the member 8. This will permit of obtaining an unequal curling of the front and rear parts 35 of the hat, the front part being less curled in order that it may be turned down (hat with front brim lowered). The eccentricity of the pot 2 with reference to the axis AA permits, in fact, of separating the hat 1 from the wheel 55 during half-a-revolution which corresponds to the front of the hat, and to approach it of the 40 wheel by the same distance, for the other half-revolution, so that for this latter half-revolution, corresponding to the back part of the hat, the brim of the hat is engaged between the members 55 and 57 to a much greater degree than for the 45 front part.

According to the shape of the hat, the form of the oval described by the axis AA can be changed by varying the eccentricity of the axis BB relatively to the axis DD. The form of the oval 50 described by the axis AA may differ, or not, from that of the oval defining the hat brim. By the use of different ovals, it is possible to obtain different curls on the periphery of the hat.

According to the dimensions of the hat and 55 of its brim, the entire oval lathe is moved towards or away from the wheel 55 by means of the hand-wheel 122, which displaces the casing 18, together with the whole mechanism, with reference to the fixed casing 20 and hence with reference to the 60 wheel 55.

Finally, by the vertical adjustment of the support 58 carrying the heating member 57, the pressure of the member 57 on the hat brim can be distributed as desired between the periphery 65 of the brim and the part situated next the tie 3.

Obviously, the said invention is not limited to the embodiment herein described and represented, which is given solely by way of example.

Having now described my invention what I claim as new and desire to secure by Letters Patent is:

1. A hat brim curling machine comprising in combination a rotary curling wheel and a curling iron between which the edge of the hat brim to be curled is adapted to be passed, a movable supporting member adapted to support the hat with the crown positioned below the brim means for rotating said curling wheel, said means being located entirely below that surface of the supporting member contacted by the hat brim and a mechanism located below said supporting member for driving said supporting member to feed the edge of the hat brim past said curling iron. 10 15

2. In a hat brim curling machine, the combination with a curling wheel and a mechanism for feeding the edge of the hat past said curling wheel, of a main driving shaft adapted to drive said curling wheel and said mechanism, clutching 20 means on said driving shaft, a pivoting arm, a curling iron adapted to cooperate with said curling wheel and mounted at the free end of said arm, a rod, connecting means between said rod and said clutching means and said arm whereby 25 said main driving shaft is unclutched and said arm is pivoted to move said curling iron away from said curling wheel when depressing said rod.

3. In a combination as claimed in claim 2, the further feature consisting in that said curling 30 iron is adjustable in height along said arm.

4. A hat brim curling machine comprising in combination a rotary curling wheel and a curling iron between which the edge of the hat brim to be curled is adapted to be passed, a movable supporting member adapted to support the hat with the crown positioned below the brim, means located below that surface of said supporting member contacted by the hat brim for rotating said curling wheel and a mechanism for driving said supporting member to feed the edge of the hat brim past said curling iron so that the tangent to the hat brim at the point of contact with the curling iron will always have a constant direction, said mechanism comprising a casing, a driving shaft journalled in said casing, a spindle carried by said shaft in parallel relation therewith, an oscillating member journalled on said spindle and provided with a cylindrical bearing 40 surface the axis of which is parallel to said spindle, a second spindle parallel to said first mentioned spindle and journalled in said oscillating member, the axis of said first mentioned spindle being located in the plane determined by the axis of said bearing surface and the axis of 45 said second spindle, at the same distance of these two axes, said second spindle being slidably carried by said casing in a direction perpendicular to its axis, a driven member journalled on said bearing surface, transmission means for connecting said first mentioned spindle to said driven member whereby they are caused to rotate one with respect to the other at respective speeds of 50 revolution which are in the ratio 2:1, said supporting member being mounted at the top of said driven member.

5. In a hat brim curling machine comprising in combination a rotary curling wheel and a curling iron between which the edge of the hat brim to be curled is adapted to be passed, a movable supporting member adapted to support the hat with the crown positioned below the brim, means located below that surface of said supporting member contacted by the hat brim for rotating said curling wheel and a mechanism for driving said supporting member to feed the edge of the hat brim past said curling iron so that the tangent to the hat brim at the point of contact with the curling iron will always have a constant direction, said mechanism comprising a casing, a driving shaft journalled in said casing, a spindle carried by said shaft in parallel relation therewith, an oscillating member journalled on said spindle and provided with a cylindrical bearing 55 surface the axis of which is parallel to said spindle, a second spindle parallel to said first mentioned spindle and journalled in said oscillating member, the axis of said first mentioned spindle being located in the plane determined by the axis of said bearing surface and the axis of said second spindle, at the same distance of these two axes, said second spindle being slidably carried by said casing in a direction perpendicular to its axis, a driven member journalled on said bearing surface, transmission means for connecting said first mentioned spindle to said driven member whereby they are caused to rotate one with respect to the other at respective speeds of 60 revolution which are in the ratio 2:1, said supporting member being mounted at the top of said driven member.

MARCEL CASSÉ.
